ISAIAH M. WILLIAMS, OF BLANCHESTER, OHIO.

Assign to himself and Calvin P. Baldwin.

Letters Patent No. 74,653, dated February 18, 1868.

IMPROVEMENT IN DITCHING-MACHINES.

The Schedule referred to in these Letters Patent and making part of the same.

TO ALL WHOM IT MAY CONCERN:

Be it known that I, ISAIAH M. WILLIAMS, of Blanchester, Clinton county, Ohio, have invented certain new and useful Improvements in Ditching-Machines; and I do hereby declare the following to be a full, clear, and exact description thereof, reference being had to the accompanying drawings, making part of this specification.

My invention relates to that class of ditching-machines in which two parallel cutters, in connection with a revolving wheel, are employed for the purpose of cutting the trench; and the first part of my improvement consists in certain devices for relieving said wheel of the dirt which has been excavated; the second part of my invention consists in an arrangement of mechanical means whereby the operator is enabled to graduate the depth of the ditch with reference to the surface of the ground; the third part of my invention relates to the excavating and elevating-wheel, which is constructed in such a manner that the radial spades with which it is armed can be readily detached, for the purpose of sharpening them, or for inserting a new one, in case any of them should become broken or otherwise injured.

The remaining parts of my invention relate to minor details of construction, which will be hereafter fully described. In the accompanying drawings—

Figure 1 is a vertical longitudinal section of a ditching-machine embodying my improvements.

Figure 2 is a vertical axial section through the elevating-wheel and its accessories.

Figure 3 is a transverse section through the machine in the rear of the elevating-wheel, showing the device for discharging the dirt.

Figure 4 is a partially-sectionized perspective view of the lower portion of the scoop or shovel.

A represents the main frame of the machine, which is supported upon the ground-wheels *a a'*, and this frame has attached to it the vibratory platform B, which carries the parallel cutters C C' and elevating-wheel D D'. The vibratory platform is coupled to the main frame in the following manner: The front end of the platform has secured to it a perforated clevis, Y, and a pin, *c*, connects said clevis with a perforated plate, A', which is attached to the transverse beam *b* of the main frame. By inserting the pin *c* in the perforations of the clevis Y and plate A', the front end of the platform can be adjusted to any height, or the pin can be so placed as to lift the cutters and wheel clear of the ground when it is desired to move the machine without cutting a trench. The elevating-wheel has a shaft, *d*, which is journalled in the vibratory platform B, and this wheel is composed of two distinct sections, D D', which are held securely together by the bolts *e*. The wheels D D' are provided with rims, E E', to which is attached by the bolts *e* a series of segmental plates, F F', which extend completely around the wheel, and the inner faces of these plates are bevelled, in order that they may the more readily enter the ground, and also to allow the excavated earth to be discharged from the wheel with the least expenditure of force. The wheel D D' is armed with a series of radial spades, G, whose bases, *g*, are dove-tailed into suitable recesses in the rims E E'. H H', &c., are a series of curved plates, whose concavity corresponds with the peripheries of the rims E E', and they are retained in position against said rims during about three-fourths of the revolution of the wheel D D'. These plates are sufficiently long to extend from one of the spades G to the next one, and the width of them is equal to the distance between the segmental plates F F'. *h h'*, &c., are links by which the plates H H' are united together, and the two thus form an endless band which extends around the greater portion of the elevating-wheel D D', and it also passes over a drum, I, which is journalled in boxes, *i*, of the standards J, that rise vertically from the vibratory platform B. The boxes *i* have a vertical movement within the V-shaped grooves *j* of the standards, and these boxes are adjusted so as to produce a greater or less degree of slackness of the band H h, by means of the wedges K which enter slots J' of said standards. The vibratory platform B, together with its elevating-wheel D D', is elevated or depressed so as to permit of a shallow or deep ditch being cut, by the following devices: Rising vertically from the main frame A are two stanchions, L L', affording support for a stout beam, M, through which passes the upper portion of a screw, N, which engages with a nut, *o*, of the winch O, and the head, *n*, of this screw sustains a stirrup, P. Attached to the vibratory platform B are two yokes, R R', which rest within the hooked ends *p p'* of the stirrup P, and it will be seen that by rotating the winch O in either direction, the platform and its accompanying wheel will be raised or lowered as desired, and that the ditch will be graded accordingly. Securely bolted to the rear por-

tion of the platform B is a scoop or shovel, S, having a step, s, for the reception of the detachable steel shoe T, which shoe is attached to the shovel by screw Q and nut q. By this means a new shoe can be fitted on to the shovel in a few minutes, in case the one in use should be broken by coming in contact with a stone or other obstruction. Secured to the rear end of the platform B is a tail-board, U, which prevents the excavated earth from falling back into the ditch as rapidly as it is raised by the elevating-wheel; and the dirt is delivered either to the right or left-hand side of the machine, according to the position of the side-board V. When this board is placed in the position represented in fig. 3, the dirt is discharged as shown, but should the board be changed to the place indicated by the dotted lines, the dirt will then be delivered at the opposite side of the machine. The side-board V has attached to it a bar, W, and by inserting said bar in either of the apertures X or X', said board will be maintained in the desired position.

The operation of my machine is as follows: The machine being drawn along by any suitable power, the cutters C C' enter the ground to the desired depth, and the segmental plates F F' being immediately behind said cutters, and in line therewith, follow the incisions made by said cutters. The width and depth of the ditch having been thus obtained, the spades G of the elevating-wheel D D' cut the earth into sections, and by the rotation of the wheel the spades compel the dirt to ascend, and it is prevented from falling out of the wheel by the shovel S. As soon as the rotation of the wheel D D' has elevated the earth to a position about as high as the shaft or axle of said wheel, the plates H, owing to the location of the drum I, assume a vertical position, and thus empty the dirt on to the rear of the platform B, from which it is delivered on either side of the machine in the manner described.

I claim herein as new, and of my invention—

1. I claim the provision in a ditching-machine of the endless band H h and drum I, operating substantially as herein described, for emptying the elevating-wheel of the excavated earth.
2. I claim constructing the dirt-elevating wheel of a ditching-machine in two sections, D D', and providing them with radial spades G, whose bases, g, are dove-tailed into the rims E E' of the wheel, and the whole secured together by bolts e, substantially as herein described.
3. I claim the screw N n, winch O, nut o, stirrups P p p', and yokes R R', arranged and operating as and for the purpose specified.
4. In combination with the elevating-wheel D D', constructed as described, I also claim the fixed and parallel cutters C C', as and for the purpose specified.
5. In combination with the elevating-wheel D D', endless band H h, and drum I, I also claim the shovel S, for the object set forth.
6. In combination with the elevating-wheel D D', endless band H h, and drum I, I further claim the slotted standard J J', groove j, box i, and wedge K, arranged and operating substantially as and for the object explained.
7. In combination with the main frame A and vibratory platform B, I claim the perforated clevis Y, pin c, and plate A', for the object stated.

In testimony of which invention, I hereunto set my hand.

ISAIAH M. WILLIAMS.
